CONCRETE FORM APPLIANCE

Chester I. Williams, Grand Rapids, Mich., assignor to Emma De Vowe, Grand Rapids, Mich.

Application October 9, 1934, Serial No. 747,582

4 Claims. (Cl. 25—131)

The invention relates to improvements in construction of monolithic structures such as concrete walls, dams, foundations, etc., by the use of forms, and more particularly it relates to an improved means and method for fastening together oppositely positioned spaced apart forms and similar devices.

An object of the invention is the provision of improved fastening means for oppositely positioned concrete forms adapted for manipulation entirely from outside the forms to fixedly fasten the forms in any one of a plurality of predetermined spaced apart positions in combination with indicating or gauge means from which the spacing of the form members can be accurately determined.

A further object of the invention is the provision of improved fastening means for concrete forms and other spaced apart members, said means being adapted for manipulation from outside the forms and adjustable to selectively hold the forms in any one of a plurality of predetermined fixed spaced apart positions.

Still another object of the invention is the provision of novel means for fastening a tie rod to oppositely positioned concrete forms or similar members, said means including spacer members fastened to the forms and adjustably fastened to the tie rod to vary the spacing of the forms or members within predetermined limits for a tie rod of selected length.

Another object of the invention is the provision of an improved tie rod unit adapted for permanent embedment in the concrete and providing means preventing rotation or longitudinal movement of the rod in the concrete.

Among the further objects of the invention is the provision of a tie rod and fastening means therefor, adapted to be externally manipulated and adjusted by one man, which may be rapidly installed and removed, the fastening means including a gauge member providing means constantly visible from outside the form for checking the accuracy of the adjustment.

A further object of the invention is to generally improve fastening means for use in concrete forms and to provide an improved method of assembly and installation whereby the entire assembled fastening means is visible to a workman while placing the same in initial position in the form.

A still further object of the invention is the provision of a tie rod and adjustable fastening means therefor, which is easily manipulated,

durable, economical and satisfactory for its intended purpose.

Many other objects and advantages of the construction herein shown and described will be obvious to those skilled in the art from the disclosure herein given.

To this end my invention consists in the novel construction, arrangement and combination of parts herein shown and described and more particularly pointed out in the claims.

Referring now to the drawings forming part of this specification and representing a preferred embodiment of the invention, Figs. 1 and 2 are, respectively, side and end elevational views of a pair of oppositely positioned forms in position 15 to pour an extension of a wall with a plurality of fastening devices embodying the invention mounted thereon in partial and fully assembled position;

Fig. 3 illustrates a fragmentary portion of one 20 side of a form member in vertical section, a tie rod and means for fastening the tie rod in selected position relative to the form member;

Fig. 4 is a view along the line 4—4 of Fig. 3;

Fig. 5 is a view along the line 5—5 of Fig. 3, 25 drawn to a larger scale;

Fig. 6 is a view along the line 6—6 of Fig. 3;

Fig. 7 is a perspective view of a pair of disassembled members which form an improved wing nut when assembled;

Fig. 8 is a view showing a portion of the fastening means in position on a vertically inclined form; and

Figs. 9 and 10 are perspective views of members forming the fastening device.

Referring now more particularly to the drawings, the numeral 10 designates a completed section of a concrete wall from which the forms have been removed. The numeral 11 generally designates a concrete form in position to pour an extension of the wall 10. While the form is shown as sectional, it is to be understood that tie rods, fastening and indicating or gauge means therefor are equally as well adapted for use with temporary form members, and with one or both of the spaced apart forms inclined to the vertical if desired. The form 11 comprises a pair of oppositely positioned side walls each constructed of a plurality of longitudinally extending boards 12 fastened to spaced apart upright members 13, 50 preferably by nails or spikes not shown.

The oppositely positioned form members are held in predetermined spaced apart relation by a plurality of fastening means each comprising an assembly of various members including a tie 55

rod 14 intended for permanent embedment in the concrete and waler rods 15 detachably fastened on each end of the tie rod and adapted for repeated use. The tie rod 14 is preferably 5 externally threaded at each end and the waler rods 15 are of larger diameter than the tie rod. The inner ends of the waler rods 15 each provide an internally threaded socket 16 adapted to receive the corresponding end of the tie rod 14. A 10 pair of projections 17 adjacent the threaded portion of the tie rod 14 hold the rod against either rotation or longitudinal movement in the concrete. The projections 17 also serve as stops or gauge members for the waler rods 15 enabling the latter to be accurately positioned by threading on the tie rod until the waler rods 15 are in contact with the projections.

A plurality of assemblies of fastening means each comprising a tie rod and a waler rod or 20 rods are arranged in the forms in any desired vertical and longitudinal spacing, the opposite sides of the form for this purpose being provided with aligned holes 18 formed in the boards 12. It is found in practice that the oppositely aligned 25 holes 18 are easily bored from one side of the forms by using an auger of suitable length.

The holes 18 are of slightly larger diameter than the waler rods 15 thereby providing a space through which the workman may see the opposite hole 18 when the waler rod is in the adjacent hole and enabling the workman to easily 30 position an assembly of a tie rod and a waler rod or of a tie rod and a pair of waler rods from one side of the form.

35 In walls of ordinary thickness a tie rod of one-half inch or smaller diameter may be used. If a one-half inch tie rod is used it is found satisfactory to use three-fourth inch waler rods and to provide one inch diameter holes 18 in the forms. 40 The workman, in positioning the assembly of tie and waler rods in the form from one side, can easily see through the one-fourth inch clearance space between the waler rod 15 and the top of the adjacent hole 18. Tie rods 14 of 45 larger or smaller diameters than one-half inch may be used in combination with correspondingly larger or smaller waler rods 15 and holes 18.

A single assembly of a tie rod 14 and a pair of waler rods 15 is adapted for use in holding the 50 side walls of the forms in any selected spaced apart relation between a predetermined maximum and minimum. For this purpose each of the waler rods 15 mounted on the tie rod 14 are adapted to be fastened against longitudinal 55 movement, relative to the form member through which it projects in any one of a plurality of selected positions by means of a tubular spacer member 19 loosely mounted on the waler rod. The inner end of the member 19 is fastened to 60 the form by threading it into the hole 18 preferably after the assembly of tie and waler rods is initially positioned in the form. The member 19 is accurately positioned relative to the form by contact of projections 20 with the outer 65 surface of the form when the member has been threaded to a predetermined position. The intermediate portion of the waler rod 15 within and adjacent the member 19 is provided with a plurality of grooves 21 arranged in pairs on opposite sides of the rod. The pairs of grooves 21 are adapted to be respectively brought into register with a pair of slots 22 provided in the member 19 by correspondingly shifting the form section on which the member 19 is mounted. The 70 75 inner bounding surfaces of the grooves 21 are

preferably parallel planes in alignment with the corresponding bounding edges of the slots 22 in the spacer member 19. Any number of pairs of grooves 21 may be provided in the waler rod 15 and may be arranged in any desired spaced longitudinal relation. Thirteen of such pairs of grooves are shown in each waler rod 15 with a spacing of four pairs of grooves per inch per length of the rod. 5

A key 23, slidably mounted in the slots 22 of the member 19, is adapted for entry into any one of the pairs of grooves 21 to thereby fasten the waler rod 15 and the spacer member 19 together. The key 23 comprises a bar having a circular aperture 24 of slightly larger diameter 15 than the member 19 with an elongated recess 25 opening into the aperture. The width of the recess 25 is slightly greater than the thickness of the waler rod material between the grooves 21 comprising a pair. Obviously by shifting the form on which the member 19 is mounted, the slots 22 in the member may be brought into registry with any pair of grooves 21. By positioning the key 23 with the bounding edges of its recess 25 in the registering slots 22 and 25 grooves 21, the waler rod 15 and the member 19 are locked together. The upper flanged edge 26 of the key 23 is adapted for lifting the key from its locking position to a position where the aperture 24 is substantially concentric with the rod 30 15 and the member 19, thereby permitting relative movement of the member 19 and the waler rod 15 to adjust the spacing of the form members to walls of different thicknesses.

Since the tie rods 15 are to remain permanently embedded in the concrete, it is desirable that the over-all length of such rods be less than the width of the wall. The slots 22 may be positioned at any convenient distance from the extremity of the threaded end of the member 19. 40 If for example this distance is made three inches, the grooves 21 on the waler rod 15 are preferably so arranged that the innermost pair is approximately four inches from the socket end of the waler rod. The outer end of the spacer member 19 extends beyond the slots 22 sufficiently 45 that the end face of the member is aligned with the inner bounding transverse edge of a pair of grooves 21 for all positions of the member when the waler rod 15 is fastened thereto by the key 23.

In order that the position of the tie rod 14 in the form may be checked from the outside, I have provided dimensions on the waler rod 15 as shown in Figs. 4 and 10, which indicate the distance the end of the tie rod is from the adjacent end of the wall. For example, when the waler rod 15 and spacer member 19 are in the relative position shown in Fig. 10, the end of the member 19 coincides with the bounding edge of the adjacent groove 21 which is marked one inch, thereby indicating to the observer that the adjacent end of the tie rod 14 is one inch from the corresponding edge of the wall. Upon movement of the form and the member 19 a distance corresponding to a spacing of the grooves which is illustrated as one-fourth inch, the waler rod reading will be one and one quarter inches, thereby indicating that the end of the tie rod 14 is one and one quarter inches from the corresponding face of the wall. The described markings and dimensions on the waler rod 15 enable the workman to check the position of the adjacent end of the tie rods 14 and also to determine the spacing of the form members. 70 75

The suggested dimensions and the suggested number and spacing of the grooves 21 permit tie rods 14 of the same length to be used in pouring walls having a thickness of not less than one inch 5 and not more than seven inches greater than the over-all length of the tie rod. The waler rods 15 and spacer members 19 are adapted for repeated use, and by providing a stock of tie rods 14 of a plurality of over-all lengths, differing 10 by six inches, the fastening devices are adapted for use in pouring walls of any practicable thickness. For example, a tie rod having a length of six inches can be used in pouring walls varying in thickness from seven inches to thirteen 15 inches; a twelve inch tie rod can be used in pouring walls of thicknesses from a minimum of thirteen inches to a maximum of 19 inches; an eighteen inch tie rod can be used in pouring all thicknesses from nineteen inches to a maximum 20 of twenty-five inches, etc.

The outer ends of the waler rods 15 have a bracket 27 loosely mounted thereon and are threaded to receive a wing nut 30. The lengths of the waler rods 15 are such that their threaded 25 ends project beyond the waler members 31 when the rod has its maximum projection inside the form. The bracket 27 provides a hub member 29 having an outwardly diverging socket 28 adapting the bracket for cooperative relation 30 with the waler members 31 on both vertical and inclined forms as respectively shown in Figs. 3 and 8. The member 29 provides bearing faces 29a and 29b with which the wing nut 30 contacts when the waler members 31 are clamped against 35 the upright members 13. In Fig. 3 the bracket 27 is shown in cooperative relation with waler members 31 of a vertical wall, the face 29a providing an abutment for the wing nut 30. In Fig. 8, the bracket 27 is shown in cooperative relation 40 to a form inclined to the vertical with the face 29b of the member 29 also providing an abutment for the wing nut 30.

The double wing nut 30 comprises two substantially identical sections 30a and 30b which are threaded or tapped while the sections are clamped together in longitudinal alignment. Each section 30a and 30b is provided with a groove 32 on one side of the tapped hole, and a corresponding projection 33 on the other side. 45 The grooves 32 and the projections 33 are positioned so that the projection on one section will enter the corresponding groove on the other section when the sections are longitudinally aligned. In their longitudinally aligned 50 contacting position the two sections can be threaded together as a unit on or off the waler rod and neither can be threaded on or off without simultaneously moving the other section. By attempting to oppositely rotate the two sections 55 in directions tending to remove the projection 33 from the groove 32, the sections will be clamped or locked together in the same manner as when two ordinary nuts are threaded into close contact. Final manipulation of the two sections 60 to lock the same as described not only holds the wing nuts in clamping contact with the hub member 29 and prevents accidental release which might otherwise occur, but also enables the wing nut to be utilized to rotate the waler or end 65 section of the tie rod and thereby disconnect it from the intermediate imbedded section. The grooves 32 and the projections 33 are provided in each of the sections 30a and 30b in order that the sections may be interchangeable. The projections and grooves are so positioned that the 70

inoperative projection on the section adjacent to the hub member 29 will clear the member as the sections are threaded into contact with the face 29a or the face 29b.

The assembly of the various members comprising the fastening means and the various steps of installations are shown in Figs. 1 and 2 and are summarized as follows:

The oppositely positioned forms are erected and spaced apart approximately the width of the 10 walls to be poured. A plurality of assembled fastening means are provided, each comprising a waler rod 15 having a tie rod 14 threaded into its socket 16 until the end of the rod 15 contacts with the projection 17. The individual 15 rods 14 and 15 so fastened together are positioned in the form by the workman inserting the same through a pair of aligned holes 18 with the tie rod in advance. The hole 18, being larger than the waler rod 15, the view of the workman is 20 unobstructed in guiding the tie rod 14 through the hole 18 in the opposite wall. The spacer member 19 is then fastened to the form and the bracket 27 and wing nut 30 are mounted on the waler rod 15 as indicated at the top of Fig. 2. 25 The waler rod 15 is shifted to bring the selected pair of grooves 21, corresponding to the width of the wall to be poured, into registry with the slots 22 in the members 19 and the rod is then locked by inserting the key 23 in the registering slots 30 and grooves.

Insertion or installation of the various assemblies of waler rods and tie rods having been completed, the workman then proceeds to the other side of the wall and threads a waler rod 35 15 onto the projecting end of the tie rod 14 until the end of the waler rod contacts with the projection 17. The spacer member 19 is then fastened to the form and the waler rod 15 is fastened to the spacer member 19 by inserting the 40 key 23 in the pair of grooves 21, corresponding to the width of the wall to be poured. The opposite form members are thereby positioned and held in predetermined spaced apart relation corresponding to the width of wall to be poured. 45 Since the assembly is fastened to the opposite form member, a slight amount of the adjacent form member inwardly or outwardly may be necessary to bring the proper grooves 21 into register with the slots 22. The bracket 27 and 50 wing nut 30 are then mounted on the waler rod 15, installation of the fastening means then being completed as indicated at the middle of Fig. 2.

Waler members 31 are next positioned as shown 55 at the lower left corner of Fig. 2, the wing nut 30 being threaded to clamp the bracket 27 against the waler members following which the nuts are locked by turning the individual sections 30a and 30b towards each other as above described. The 60 workman then returns to the other side of the form from which he initially inserted the fastening means and then secures the waler members 31 to the fastening means in the same manner as described for the opposite side and thereby 65 completes the assembly of the forms in predetermined spaced apart relation.

After the concrete is set, disassembly and removal of the fastening means and forms is easily accomplished by detaching the waler rods 15 from 70 the tie rods 14. This is accomplished by turning the waler rods to unthread the same from the tie rods 14 which are held against rotation by projections 17. In the repeated use of sectional forms it is not necessary to remove the spacers 75

19 from the forms. The same waler rods, brackets and wing nuts may be repeatedly used and with slight or no shifting of the wing nuts 30 if used in pouring walls of the same thickness.

5 Thus it will be seen that I have provided novel
fastening means adapted for interchangeable
mounting on oppositely positioned form members
or the like, whereby such members may be ma-
nipulated entirely from outside the forms to fix-
10 edly fasten the form members together in any
one of a plurality of predetermined spaced apart
positions, the fastening means including gauge
members, observable from the outside of the forms
and providing indicia by means of which the
15 spacing of the forms can be easily read or deter-
mined.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

25 What I claim as new and desire to secure by Letters Patent is:

30 1. A fastening device for oppositely positioned
form members having aligned holes arranged in
pairs, said device comprising a pair of tubular
members respectively mounted on the outside of
said form members with the inner ends position-
35 ed in said holes, a tie rod positioned in said
tubular member, said rod comprising an inter-
mediate section positioned between and stopping
short of said form members and end sections hav-
ing threaded engagement with said inner section,
50 a wing nut having threaded engagement with the
outer end of each of said end sections and providing
means for locking engagement therewith to
prevent its rotation relative to the sections, said
tubular members each provided with a slot and
55 said end sections each provided with a plurality
of grooves adapted to register with said slots upon
relative movement of the form member and tie
rod, key members insertable in said registering
60 slots and grooves to lock said tubular members
and tie rods against relative movement, and means
on each of said outer sections indicating the dis-
tance from the adjacent form member to the con-
65 tiguous end of said inner rod section.

2. A fastening device for oppositely positioned form members having aligned holes arranged in pairs, said device comprising a pair of tubular members respectively mounted on the outside of

in said holes, a tie rod positioned in said form members, said rod comprising an intermediate section positioned between and stopping short of said form members and end sections having threaded engagement with said inner section, said tubular members each providing a pair of oppositely positioned slots, said end sections each providing a plurality of pairs of grooves adapted to register with said slots upon relative movement of the form members and tie rod, and key 10 members insertable in said registering slots and grooves to lock said tubular members and tie rod against relative movement. 5

3. A device for holding a pair of oppositely positioned wall forms in selectively spaced-apart relation, said device comprising a pair of fastening members adapted to be fixedly mounted on the outside of the respective form members, a rigid tie member adapted to extend through aligned holes in said form members with its projecting end portions respectively in closely spaced contiguity to said fastening members, the end portions of the tie member providing a plurality of longitudinally spaced sockets and each fastening member providing a slot adapted to successively register with said sockets as the projection of the tie member from the wall forms is increased or diminished, and key members insertable in said slots and registering sockets and operable thereby to lock the tie member against movement relative to the wall forms.

4. A device adapted for holding a pair of oppositely positioned wall forms in selectively spaced-apart relation, said device comprising a pair of fastening members adapted to be fixedly and detachably mounted on the outside of the form members, a rigid tie member adapted to extend through aligned holes in said form members with its projecting end portions respectively in closely spaced contiguity to said fastening members, the end portions of the tie member providing a plurality of longitudinally spaced sockets and each fastening member providing a slot adapted to successively register with said sockets as the projection of the tie member from the wall forms is increased or diminished, and key members insertable in said slots and registering sockets and operable thereby to lock the tie member against movement relative to the wall forms, said tie member comprising a middle rod and end rods removably secured to the middle rod, the overall length of the middle rod being less than the minimum selected spacing of said wall forms.
